UNITED STATES PATENT OFFICE.

HARMON SHARP, OF GARFIELD, WASHINGTON.

MECHANICAL MOVEMENT FOR APPLE-CORERS.

1,259,145.

Specification of Letters Patent. Patented Mar. 12, 1918.

Application filed May 29, 1917. Serial No. 171,733.

To all whom it may concern:

Be it known that I, HARMON SHARP, a citizen of the United States, residing at Garfield, in the county of Whitman and State of Washington, have invented certain new and useful Improvements in Mechanical Movements for Apple-Corers, of which the following is a specification.

This invention relates to vegetable cutters, 10 and more particularly to apple coring and cutting machines.

The object of the invention is to provide a simply constructed and efficient apparatus with which an apple may be cored and cut 15 into segments in a single operation.

Another object is to provide an apparatus of this character with interchangeable cutters whereby the size of the pieces in which the apple is to be cut may be varied.

Another object is to provide an apparatus equipped with an apple holder and with a cutter which are movable toward and away from each other whereby an apple may be held and cut during their movement toward 25 each other and space provided for the insertion of another apple when they move away from each other.

With the foregoing and other objects in view, which will appear as the description 30 proceeds, the invention resides in the combination and arrangement of parts and in the details of construction hereinafter described and claimed, it being understood that changes in the precise embodiment of the invention herein disclosed may be made within 35 the scope of what is claimed without departing from the spirit of the invention.

In the accompanying drawings:—

Figure 1 represents a side elevation of an 40 apparatus constructed in accordance with this invention, an apple being shown in dotted lines ready to be cored and cut,

Fig. 2 represents a rear elevation thereof,

Fig. 3 is a longitudinal vertical section 45 taken on the line 3—3 of Fig. 2,

Fig. 4 is a horizontal section taken on the line 4—4 of Fig. 2, and

Fig. 5 is a detail perspective view of the upper portion of one of the rack bars.

In the embodiment illustrated, the apparatus constituting this invention comprises a base plate 1 of any suitable shape and size 50 sufficient to support the parts of the apparatus constituting this invention. This plate is here shown rectangular in form and rising therefrom are two standards 2 and 3 spaced

laterally from each other and provided on their inner faces with longitudinally extending guides in the form of grooves 4 which are designed to receive ribs 5 carried by rack bars 6 and 7 which are designed to reciprocate in said standards for a purpose presently to be described. The teeth 8 of these rack bars face each other and are designed to be engaged by two pinions 9 and 10 65 which are mounted to rotate between said bars, being journaled in two uprights 11 and 12 rising from the base plate 1 and which are secured and braced in position by a cross bar 13 secured to the upper ends of 70 the standards 2 and 3. The upper ends of the uprights 11 and 12 have laterally extending arms as 14 which are designed to abut at their free ends and operate as spacers for said uprights, being held in operative 75 engagement by a bolt 15 which passes through the cross bar 13 and through the two uprights 11 and 12 as is shown clearly in Fig. 3.

A reinforcing and supporting band 16 extends around the bottoms of the standards 2 and 3 and the uprights 11 and 12 and is provided with laterally extending flanges or base plates 17 which are secured to base 80 1 by screws or in any other suitable manner. (See clearly Figs. 3 and 4.) This band 16 is shown fastened to the uprights 2 and 3. The lower ends of the uprights 11 and 12 are provided with outwardly projecting laterally extending feet as 11' and 12' which 85 are countersunk in the base plate 1 and preferably secured therein by screws as is shown clearly in Fig. 3 so that said uprights are firmly and rigidly connected with the base plate and thus adapted to withstand any 90 strains to which they may be subjected. The pinions 9 and 10 are arranged one above the other in longitudinally spaced relation and the lower pinion 9 has one of its journals 95 extending through the rear upright 12 and 100 made angular in transverse section as shown at 18 to provide a connection for the crank handle 19 as is shown clearly in Fig. 2.

The rack bar 6 has a laterally extending casting 20 projecting from its upper end and 105 extending approximately across the space between the standards 2 and 3, said casting being here shown triangular in form with a depending spur 21 which constitutes the holder for the apple being designed to be 110 inserted in one end thereof. A boss as 22 also depends from the casting 20 and oper-

ates as a stop for limiting the insertion of the spur within the apple.

Projecting laterally from the lower end of the rack bar 7 is a similarly shaped casting 23 which carries a cutter 24 constructed in the form shown in Figs. 1, 3 and 4. This cutter as here shown comprises a central tube 25, one end of which is designed to be detachably mounted in an opening 26 formed in the casting 23 and which is limited in its insertion by a shoulder 27 formed in said opening as is shown clearly in Fig. 3. Arranged around the periphery of this tube 25 are a plurality of cutting blades 28, any desired number of which may be employed, four being here shown arranged at diametrically opposite points, although obviously any other desired number may be used. These blades 28 have their cutting edges extended beyond the upper end of the tube and rounded as shown at 29 to facilitate their engagement with the apple to be cut as is shown clearly in Fig. 1. These blades extend substantially throughout the length of the tube 25 tapering toward their inner ends and operate to resist the strain exerted by the forcing of the blades into the apple which is occasioned by the movement of the cutter 24 toward the holder 21, it being obvious that when the crank handle is turned that the reciprocation of the rack bars 6 and 7 produced thereby will operate to move the cutter and holder toward and away from each other. The movement of these members toward each other will operate to simultaneously core and cut the apple into segments, the core being cut out by the tube 25, the upper edge of which is sharpened as shown at 30 for this purpose and the blades 28 which project above the upper end of said tube will be forced into the apple and cut it into segments. The core so cut will drop down through the tube 25 and is preferably caught in a bag 31 here shown arranged under said tube for this purpose. This bag 31 is provided at its upper end with hooks 32 which are designed to detachably engage the outside ends of a rod 33 which extends transversely through the casting 23. This bag 31 has an openable closure 34 which is here shown in the form of an outturned flap connected with the bag by hooks and eyes indicated at 35.

From the above description it will be understood that by turning the crank handle 19 in one direction the rack bars will be reciprocated so as to carry the apple holder 21 and the cutter 24 away from each other

Copies of this patent may be obtained for five cents each, by addressing the "Commissioner of Patents, Washington, D. C."

into the position shown in Figs. 1 and 3 and when the apple has been properly positioned either on the cutter or suspended on the holder 21, and the handle turned in the opposite direction, these members will move toward each other and thereby force the cutter upward and the apple downward, coring and simultaneously cutting it into segments, and that the cores will drop through the tube 25 into the bag 31, while the segments will drop on the outside thereof and may be caught in any suitable receptacle.

The pinion 10 is utilized to steady and guide the bars in their reciprocatory movement.

From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

I claim:

In an apparatus of the class described, a base plate, a pair of laterally spaced standards rising therefrom and having longitudinally disposed guides on their inner opposed faces, rack bars having co-operating members mounted to slide on the guides of said standards and provided with teeth, the teeth of one rack bar being arranged opposite those of the other, uprights disposed between said standards, a pair of vertically spaced pinions journaled in said uprights and meshing with said rack bars, a crank handle connected with one of said pinions, a member to be reciprocated projecting laterally from one of said rack bars and a co-operating member projecting laterally from the other and in alinement with said first mentioned member whereby on the actuation of said crank handle the bars are reciprocated to move said members toward and away from each other.

In testimony whereof I affix my signature in presence of two witnesses.

HARMON SHARP.
